UNITED STATES PATENT OFFICE.

JAMES HENRY THOMPSON, OF HOLLIDAYS COVE, WEST VIRGINIA,

ELECTRON-DISCHARGE DEVICE.

Application filed November 17, 1924. Serial No. 750,340.

To all whom it may concern:

Be it known that I, JAMES HENRY THOMPSON, a citizen of the United States, residing at Hollidays Cove, in the county of Hancock and State of West Virginia, have invented certain new and useful Improvements in an Electron-Discharge Device, of which the following is a specification, reference being had therein to the accompanying drawings.

This invention relates to an electron discharge device in the nature of an electron tube or bulb of the character commonly employed for various purposes, such as detecting, transmitting and amplifying electric signals; particularly in the art of wireless telegraphy and telephony.

Electron discharge devices of this character are in common use and their principle of operation is well known. The present invention does not involve any new mode of operation but is designed to provide an improved structure in an article of this sort, of such a nature as to render it possible to readily repair or replace the filament of the device without danger of disturbing the other elements thereof.

It is a further object of the invention to so dispose the cathode or filament that while it is placed in position to lend itself to ready repair, it will also be so disposed as to be in the most efficient relation to the electrode and anode plates. To this end the filament is disposed in the form of a double diagonal as will be hereinafter set forth.

In the accompanying drawing:

Figure 1 is a side elevation of a tube or bulb of the character described, constructed in accordance with the invention.

Figure 2 is a plan view thereof.

Figure 3 is a perspective view of one of the filament supporting posts upon an enlarged scale, and

Figure 4 is an underside plan view of the base or stem of the bulb, illustrating the relation of the several terminals.

Like numerals designate corresponding parts throughout the several figures of the drawing.

Referring to the drawing, 5, designates the bulb and 6 the base or stem of the bulb, these parts being of known design. It is to be understood that the shape of the bulb makes no difference but that I contemplate

employing a bulb of any suitable size or shape. Sealed into the stem of the bulb are two upstanding filament supporting posts 7 and 8. Those portions of these posts which lie within the bulb 5 are preferably of substantially quarter-round form and carry extensions, or ears 9, 9^a and 10, 10^a. These extensions receive short binding screws 11, which preferably have slots 12 cut in their smaller ends; said slots providing means by which the screws may be tightened with a screw driver as will be hereinafter set forth.

The cathode or filament, made of any suitable refractory material such, for example, as tungsten, consists of the strands 13 and 14 which are disposed in the double diagonal formation shown, strand 13 extending from the ear 9 of post 7 to the ear 10^a of post 8 and the strand 14 extending from the ear 9^a of post 7 to the ear 10 of post 8. These strands are disposed upon opposite sides of the electrode plate 15 and they are disposed between anode plates 16 and 17. All of these plates are corrugated as best illustrated in Figure 2, to give them the necessary rigidity to eliminate vibration. The anode plates 16 and 17 are carried by posts 18 and 19, the lower ends of which are connected by the conductors, indicated at 20 and 21, to a common terminal post 22 marked "P" for "plate." The electrode plate 15 is carried by the post 23, which is connected by a conductor, indicated at 24, with a terminal post 25 marked "G" for "grid." The lower ends of the posts 7 and 8 are connected by conductors 26 and 27 with terminal posts 28 and 29 marked "F" for "filament."

Since the posts 7 and 8 are of quarter-round formation and since those portions of the screws which are slotted for the reception of the screw-driver are exposed at the inner faces of the said posts, it follows that a screw driver to be engaged with said screws may approach the screws at such an angle and in such relation to the anode plates that there will be no danger of touching the anode plates and disturbing their position. Furthermore the filament constituted by the strands 13 and 14 is so disposed in the open spaces between the electrode plate and the anode plates as to be readily slipped therefrom for purposes of repair. The surfaces of the anode plates are preferably made somewhat smaller than the sur-

face of the controlling electrode plate. It is to be particularly noted that while the cathode or filament is of the utmost simplicity, consisting merely of two strands, and those readily and freely removable through the open space between the electrode plate and the anode plates, yet these filaments are so disposed, by reason of their double diagonal disposition, as to bring practically all of the surface of the several plates in opposition thereto, so that maximum efficiency in operation will be secured.

It is to be understood that the invention is not limited to the precise construction set forth but that it includes within its purview whatever changes fairly come within either the terms or the spirit of the appended claims.

Having described my invention, what I claim is:

1. An electron discharge device comprising two separate filamentary cathodes adapted to emit electrons, a controlling electrode plate enclosed by said cathodes and within electron receiving relation thereto said cathodes being so disposed as to form a double diagonal across the controlling electrode plate, upon the opposite sides thereof

and extending from corner to corner and beyond the confines thereof.

2. An electron discharge device comprising a pair of anode plates and a controlling electrode plate disposed therebetween, in combination with a pair of separate filamentary cathode elements, one lying upon each side of the controlling electrode plate and between said electrode plate and the anode plates, said cathode elements being inclined obliquely and in opposite directions across the faces of said plates and extending beyond the side edges thereof.

3. An electron discharge device comprising a controlling electrode plate and a pair of anode plates upon opposite sides of the electrode plate, a pair of filament supporting posts disposed at the opposite ends of the electrode plate and outwardly thereof and separate filaments constituting cathodes extending between said posts and disposed in double diagonal formation, said filaments extending through the spaces between the electrode plate and the anode plates.

In testimony whereof I hereunto affix my signature.

JAMES HENRY THOMPSON.
